UNITED STATES PATENT OFFICE.

ANDREW ENGLE, OF NEWTON, IOWA.

PORTABLE INCINERATOR.

Application filed June 21, 1926. Serial No. 117,349.

The object of this invention is to provide an improved portable device adapted for the reception of waste matter such as garbage, and to dispose of such waste matter by 5 dehydration and combustion.

A further object of this invention is to provide, in a portable incinerator, improved means for receiving and imparting a delayed traveling motion to waste products and at 10 the same time subjecting such products to the influence of heat, whereby at the end of the travel the products may be deposited in a fire box and successfully consumed.

A further object of the invention is to 15 provide improved means for feeding waste products to a fire box after subjecting them for a considerable period to the drying influence of heat.

With these and other objects in view, my 20 invention consists in the construction, arrangement and combination of elements hereinafter set forth, pointed out in the claim and illustrated by the accompanying drawing, in which—

25 Figure 1 is a plan view of a portion of my improved portable incinerator.

Figure 2 is a side elevation of the same.

Figure 3 is a longitudinal section on the line 3—3 of Figure 1.

30 Figures 4 and 5 are cross-sections on the lines 4—4 and 5—5 respectively of Figure 3.

The device comprises a housing or box 10 formed of sheet metal such as boiler sheets suitably reinforced and mounted on trucks

35 11, provided with a pole 12 or otherwise suitably arranged to be drawn along the streets. The housing 10 is enclosed on all sides, but preferably there is a large opening in its top closed by a hinged door 13.

40 Across one end of the housing 10 is a hopper 14, and a platform 15, with steps 16, is arranged below said hopper. The opposite end portion of the housing is formed as a fire box 17 having a grate 18 beneath which

45 is an ash pan 19. A door 20 in one side of the housing is formed integral with the ash pan 19, and a door 21 in the end of the housing gives access to the fire box. Any suitable means may be provided for producing

50 combustion in the fire box, such as one or more oil or other hydrocarbon burners 22 arranged adjacent the grate 18. The burners 22 may be fed by a pipe 23 leading from a supply tank 24 mounted in elevated posi-

55 tion at one side of the housing, and preferably a blower device 25 also is provided,

mounted at the side of the housing and adapted to supply forced draft to the burners through ducts 26. A motor 27 of any approved and suitable type also is mounted at one side of the housing and is adapted to supply power for the blower 25 and for other purposes hereinafter set forth. The blower device is driven from the motor by a chain or belt 28.

60 Mounted side by side in and extending longitudinally of the upper portion of the housing 10 are a number of tubular dryers 29, in this instance three in number. The dryers 29 are journaled for rotation in the 65 end walls of the housing or in bearings 30, and at one end they communicate with and are adapted to receive substance from the hopper 14. From their initial ends the dryers 29 incline downwardly somewhat in the 70 housing and pass through the fire box 17 above the burners 22, to which they are adapted to discharge their contents through large openings 31 formed in their sides, or any other suitable manner of discharge into 75 the fire box may be provided. At their terminal ends the rotary dryers 29 are provided with suitable gearing 32 outside the 80 housing, by which they are conjunctively rotated, and driving means such as sprocket 85 gearing 33 is provided for driving said dryers from the motor 27, such sprocket gearing in this instance being associated with a transverse shaft 34 at the end of the housing having bevel gear connections 35 with one 90 of the dryers.

95 Waste material such as garbage is dumped into the hopper 14 and enters the rotary dryers 29, and as they are slowly rotated the substance travels slowly down the incline toward the fire box and is dried by heat therefrom, products of combustion passing along the housing and in contact with the dryers to a flue 36 on the housing near the hopper. This slow travel dehydrates the substance and thoroughly dries it so that the major portions thereof are combustible and are consumed when deposited upon the burners 22 or the grate 18. 100 As such products usually contain large quantities of carbon, it follows that when thus dried and deposited they will burn readily and in fact will provide considerable available fuel for producing heat to dry quantities of waste material subsequently received in the dryers. After combustion is well established, it will often be found that some or 105 110

perhaps the major portion of oil or other auxiliary fuel supplied to the fire box may be withheld and combustion be continued wholly or in large part by the dried waste products deposited by the dryers.

If desired a cylindrical beater device 37 may be mounted for rotation in the hopper 14, provided with suitable teeth or the like for picking, tearing or otherwise disinte-

10 grating the mass of waste substance deposited in the hopper, and causing it to travel toward the mouths of the rotary dryers. The beater device 37 is driven by a chain or belt 38 from the engine 27.

15 A transverse partition 39 preferably is arranged between the fire box 17 and remaining portion of the housing interior and extending from the grate up to the dryers 29, so that heated products of combustion 20 are caused to first travel upwardly and around the dryers and are delayed somewhat in their passage to the flue 36.

This provides a very convenient portable means of disposing of garbage and the like 25 at small cost. It may be drawn about the streets and alleys of a city and the garbage deposited therein as it is collected, and immediately consumed. Any portions which are not consumed can of course be removed 30 from time to time and otherwise disposed of.

but it is believed the greater portion of all kitchen and household garbage can thus be consumed. It thus saves the cost of lengthy transportation of the substance and of a separate and usually expensive incinerator 35 or rendering plant.

The fire box may be provided with a heat-resisting lining 40 of asbestos or other suitable material.

The slow rotation of the dryers also serves 40 to agitate the contents, and to prevent undue heating of the material of which they are made.

I claim as my invention—

A portable incinerator, comprising a housing arranged for transportation, a fire box in one end of said housing, means for producing combustion in said fire box, a hopper at the other end of said housing, a plurality of tubular dryers arranged side by side in 50 the upper portion of said housing and inclining downwardly from said hopper to the fire box and provided with discharge means to the latter, the discharge means of each dryer being staggered circumferentially relative to the discharge means of adjacent dryers, and means for rotating said tubular dryers.

ANDREW ENGLE.
